(57) **CLAIM**

The ornamental design for a portable commode, as shown and described.

DESCRIPTION

FIG. 1 is a perspective view of an upper side of the portable commode in an expanded position;

FIG. 2 is a perspective view of a lower side of the portable commode in the expanded position;

FIG. 3 is a front elevation view of the portable commode in the expanded position;

FIG. 4 is a side elevation view of the portable commode in the expanded position, the opposing side view being a mirror image of the side view shown;

FIG. 5 is a rear elevation view of the portable commode in the expanded position;

FIG. 6 is a top view of the portable commode in the expanded position;

FIG. 7 is a bottom view of the portable commode in the expanded position;

FIG. 8 is a perspective view of the portable commode in the expanded position with a bag affixed thereto;

FIG. 9 is a perspective view of a front side of the portable commode in a retracted position;

FIG. 10 is a perspective view of a rear side of the portable commode in the retracted position;

FIG. 11 is a side elevation view of a first side of the portable commode in the retracted position;

FIG. 12 is a front elevation view of the portable commode in the retracted position;

FIG. 13 is a side elevation view of a second side of the portable commode in the retracted position;

FIG. 14 is a rear elevation view of the portable commode in the retracted position; and,

FIG. 15 is a top view of the portable commode in the retracted position, the opposing bottom view being a mirror image of the top view shown.

The broken lines in FIG. 8 are for the purpose of illustrating environment and form no part of the claimed design.
